תְּבִזְבֵּחַ 4.

תְּבִזְבֵּחַ 5.

תְּבִזְבֵּחַ 6.

FIG. 1 is a perspective view of a blood filtration unit showing our new design;

FIG. 2 is a top plan view of the unit shown in FIG. 1;

FIG. 3 is a bottom view of the unit shown in FIG. 1;

FIG. 4 is a side view of the opposite side of the unit shown in FIG. 1;

FIG. 5 is a side view of the left end of the unit shown in FIG. 4;

FIG. 6 is a side view of the right end of the unit shown in FIG. 4;

FIG. 7 is a perspective view of an alternate embodiment of the unit;

FIG. 8 is a side view of the opposite side of the unit shown in FIG. 7; and

FIG. 9 is a top plan view of the unit shown in FIG. 7. We claim:

The ornamental design for a blood filtration unit, as shown and described.
